To all whom it may concern:

Be it known that I, PAUL GROEBER, a citizen of the United States, residing in the city of New York, county and State of New York, 5 have invented and produced a new and original Design for a Wall or Ceiling Covering, which is especially intended as a wall-hanging, of which the following is a specification.

The drawing represents a front plan view of 10 the design.

The design is of a composite character, being partly Egyptian and partly Eastlake. The center of the pattern shows a rosette, a, radiating from which are fan and spear-head like figures 15 b b, treated in the Egyptian style. This part of the design is inclosed by an elongated oval, c c, at the four sides and extreme ends of which are placed rosettes d d in the Eastlake style.

Serolls e e further inclose the pattern. The interstices of the design are filled in with 20 scroll-work, small rosettes, and other ornamentation.

I claim—

The design herein shown and described, consisting of a central rosette, from which radiate 25 fan and spear-head shaped figures, all being inclosed within an elongated oval, and rosettes at the ends and on the four sides of the oval, and the remainder of the design being filled in with scrolls, rosettes, and other ornamental 30 figures and lines.
